ATTORNEY

UNITED STATES PATENT OFFICE

MORITZ SCHENKEL, OF BERLIN-CHARLOTTENBURG, GERMANY, ASSIGNOR TO WESTINGHOUSE ELECTRIC & MANUFACTURING COMPANY, A CORPORATION OF PENNSYLVANIA

MERCURY-ARC RECTIFIER

Application filed May 20, 1930, Serial No. 454,044, and in Germany June 4, 1929.

My invention relates to mercury-arc rectifiers, and particularly to such rectifiers as have common grids for a plurality of electrodes.

5 Prior to my invention, considerable difficulty was experienced with mercury-arc rectifiers because of back-firing. This back-firing was caused by several conditions, such as condensed mercury in the anode spaces or too 10 high vapor pressure in the rectifier itself, also the grids commonly employed to prevent such back-firing so restricted the discharge path that the current density in particular portions of the grid probably materially augmented 15 the tendency to back-fire.

It is an object of my invention to provide a rectifier having a grid common to all of the anodes so that the discharge path is not unduly restricted by the presence of the grid.

20 It is a further object of my invention to provide a rectifier having a low vapor pressure in the vicinity of the anode.

Other objects and advantages of my invention will be apparent from the following detailed description, taken in conjunction with 25 the appended drawing, in which:

The single figure is a sectional elevation of a rectifier embodying my invention.

The apparatus disclosed in the drawing 30 comprises a rectifier having a metal container 1 and a plurality of anodes 2 therein. In the bottom of the tank is a reconstructing cathode 3 preferably of mercury. The anodes 2 are preferably arranged in annular formation in the top of the tank. Each of the anodes is provided with a shield 4 of any desired configuration.

35 Suspended in the central portion of the tank, is a ring cooler 5 providing a condensing chamber 6 in the central portion of the tank. The condensing chamber 6 is so placed that mercury vapor rising from the cathode 3 will normally pass into it.

An annular grid 7 is placed between the 45 ring cooler and the side walls of the tank to be in the discharge path from each of the anodes 2. The common grid permits the arc to pass through without material restriction. In this manner, the arc density is practically constant throughout the total arc

length. The grid serves the further purpose of materially reducing the amount of mercury vapor entering the anode space.

The individual anode shields 4 may be provided with individual grids 8 as a further precaution against back-firing.

In operation, the arcs from the various anodes play through the common grid 7 in such manner as to be practically unrestricted. The grid, however, materially restricts the 60 upward flow of mercury vapor into the anode spaces to such degree that the tendency to back-fire is materially reduced.

The annular condensing chamber 6, by providing a convenient condensing surface, prevents 65 mercury vapor from flowing up through the center of the tank and returning through the anode space.

I do not wish to restrict myself to the specific embodiment of my invention herein shown and described since it is apparent that it may be modified without departing from the spirit and scope of my invention, as defined in the appended claims.

I claim as my invention:

1. A mercury-arc rectifier comprising a tank, a plurality of anodes disposed in annular formation in said tank, a vaporizable cathode in said tank, an annular condensing chamber disposed within the anode circle, an individual anode shield for each of said anodes, an annular grid common to all of said anodes and substantially filling the space between said condensing chamber and the wall of said tank.

2. A mercury-arc rectifier comprising a tank, a plurality of anodes in said tank, a vaporizable cathode in said tank, a condensing chamber in said tank so positioned as to receive a large part of the vapor rising from said cathode, and a grid common to all of said anodes, said grid having an opening therethrough for providing an unobstructed entrance to said condensing chamber.

3. A mercury-arc rectifier comprising a metal tank, a plurality of anodes in said tank, a reconstructing cathode in said tank, a ring cooler in the central portion of said tank, and an annular grid common to all

of said anodes and filling the space between said ring cooler and the walls of said tank.

4. A mercury-arc rectifier comprising a metal tank, a plurality of anodes in said tank, a vaporizable reconstructing cathode in said tank, an individual anode shield on each of said anodes, a grid between said cathode and said anodes, said grid being common to all of said anodes, a condensing chamber 10 in the tank, said grid having an opening for providing a direct vapor passage from the cathode to the condensing chamber.

5. A mercury-arc rectifier comprising a metal tank, a plurality of anodes in said tank, a vaporizable reconstructing cathode in said tank, an individual anode shield on each of said anodes, a grid between said cathode and said anodes, said grid being common to all of said anodes, and individual 20 grids for the respective anodes.

In testimony whereof, I have hereunto subscribed my name this 25th day of April, 1930.

MORITZ SCHENKEL.
